UNITED STATES PATENT OFFICE.

JAMES KELLEY, OF RICHMOND, INDIANA.

WIRE-AND-PICKET-FENCE MACHINE.

SPECIFICATION forming part of Letters Patent No. 431,772, dated July 8, 1890.

Application filed January 14, 1888. Serial No. 260,791. (No model.)

To all whom it may concern:

Be it known that I, JAMES KELLEY, residing at Richmond, in the county of Wayne and State of Indiana, have invented certain 5 new and useful Improvements in Fence-Making Machines, of which the following is a specification.

My invention relates to that class of fence-machines known as "picket-fence looms;" 10 and it has for its object to provide a machine which will automatically feed the picket between the wires, twist same in reverse direction at each edge of the picket, feed the same forward, wind same upon the bolt-shaft, and 15 adjust said shaft so as to always wind said fence in the same horizontal plane, such movements being accomplished by suitable intermediate gearing devices connected with the drive-shaft, whereby the movement of the machine 20 may be continuous and require the service of only one man or boy to run it.

It has also for its object to provide means for adjusting the wires so that the pickets may be woven in place, either close together 25 or at some distance apart, and whereby different widths of pickets may be used.

To this end my improved fence-making machine consists in certain novel features of construction and peculiar combination of parts, 30 all of which will be hereinafter fully described in the annexed specification, and particularly pointed out in the claims, reference being had to the accompanying drawings, in which—

Figure 1 is a top plan view of my improved fence-making machine. Fig. 1^a is a detail view, hereinafter referred to. Fig. 2 is a side view thereof. Fig. 3 is a vertical transverse section of the same, taken on the line 3 3, Fig. 1. Fig. 4 is a vertical longitudinal section 40 taken on the line 4 4, Fig. 1. Fig. 5 is a detail cross-section on the line 5 5, Fig. 3. Fig. 6 is a detail perspective view of the spring-actuated picket-feeder. Fig. 7 is a cross-section on line 7 7, Fig. 1. Fig. 8 is a detail view, hereinafter referred to. Fig. 9 is a detail cross-section of the tension device. Fig. 45 10 is a detail view of the shifter-arm, and Fig. 11 is a detail view of the segmental rack and the gear I.

In the drawings, A indicates the main frame, which may be constructed of either wood or iron, and which is formed of the rect-

angular shape shown, on the cross-bars a a of which is journaled the main shaft B, such shaft being disposed approximately about 55 midway between the bottom and top of the frame and provided at one end with a drive-wheel, as shown.

C C indicate flanges or disks, which are securely fixed on said shaft, between which is 60 loosely journaled on said shaft a large grooved pulley Z, the purpose of which will appear farther on, said pulley being disposed near one end of the shaft B, and still nearer such end I provide said shaft with a pinion D, 65 which gears with a cog-gear E', which is securely attached to the shaft E, journaled in the frame A and disposed below and parallel to the shaft B.

On the forward end of the shaft E is at- 70 tached a crank F, which is connected by means of the rod f with the segment or operating-rack G, the lower end of such segment being bifurcated, as at g g, and pivoted on the rod g', journaled in the main frame, as 75 shown. The upper peripheral edge G' of this segment is formed with a central toothed section G² and smooth end sections G³ G³, for a purpose hereinafter explained.

H denotes a short shaft arranged parallel 80 to the main shaft and disposed directly under the table or bed portion of the machine, such shaft being provided with a pinion I, which is disposed over the segment G and is adapted to be engaged by the rack-teeth G² 85 when said segment is oscillated on its pivot.

H' indicates a spur-pinion secured on the shaft H, which meshes with the lower toothed face J' of a reciprocating rack-bar J, arranged to operate at right angles to the shafts B and 90 H, as most clearly shown in Fig. 1 of the drawings. The upper face of the bar J is also provided with a toothed portion J³, which normally is in engagement with the cogged rims K' of the twister-disks K, one of such 95 disks being shown in section in Fig. 3, said disks being journaled in metal plates k k, secured and depending from a transverse beam L, held upon the frame A, as shown.

The disks K, of which there may be two 100 or more employed, are each formed of a hollow hub-section 1, a toothed rim K', and the cross-pieces 2 2, provided with wire-passages 3 3, which register with similar passages m

- m* in the tension-posts *M M*, secured at the front end of the machine, such posts being formed of the vertical plates having the wire-passages *m* and the metal brackets *m' m'*, provided with the spring-cushions *m² m²* and the pressing-washers *m³*, such cushions and washers being disposed just inside of the plates *M*, the washers and cushions being adjustably held by means of the adjusting-screws *m⁴ m⁴*.
- 10 So far as described only the means for operating the twister-disks have been referred to. From such description it will be seen that when the shaft *B* is revolved the shaft *E* will be revolved, and the movement thereof will be communicated to the oscillating segment *G*, the toothed section thereof engaging the cog-gear *I* on the shaft *H*, such shaft causing the rack *J* to move to the left as the segment moves to the right, and vice versa.
- 15 It will thus be seen that the twister-disks *K* will be revolved in opposite directions, thereby twisting the wires in reverse directions on opposite edges of the pickets in a manner presently explained. As before stated, the picket-feeding devices operate automatically, such operation being effected by the movement of the main shaft.
- 20 It will thus be seen that the twister-disks *K* will be revolved in opposite directions, thereby twisting the wires in reverse directions on opposite edges of the pickets in a manner presently explained. As before stated, the picket-feeding devices operate automatically, such operation being effected by the movement of the main shaft.
- 25

Now, by referring to Fig. 1 of the drawings it will be seen that the picket support or bed consists of a transverse bar *N*, arranged in front of and just below the lower edge of the twister-disks, such bed having a detachable extension *O*, which projects beyond one side of the machine, such extension being formed with a longitudinal slot *o*, in which operates a spring-actuated picket pusher *P*, (shown in detail in Fig. 6,) and which consists of a body portion *P'*, provided with grooves *p*, adapted to engage plates *n n*, fitted to the under side of the extension *O*, as most clearly shown in Fig. 7 of the drawings, such plates forming guides for holding said pusher in position. The pusher *P* is provided at its front with a vertical finger *P²*, pivoted at its lower end to the body *P'*, such finger having a rearwardly-extending base *p²*, which limits the rearward movement of said finger. A spring *p³*, connected at one end to the finger and at its other end to the body portion *P'*, normally holds said finger in a vertical position. The finger *P²* is also provided with grooves *p⁴ p⁴* near its upper end, which engage plates *Q Q*, secured to the upper face of extension *O*, such plates, however, stopping short at each end of the slot, as shown.

At the front edge of the extension *O*, I provide a vertical plate *R*, which forms a guide for the picket when placed in position on the extension. At the outer end of the extension *O*, below the same, I journal a pulley *S*, over which passes a cord *T*, one end of which is secured to the rear end of the pusher *P*, while its opposite end is secured to the grooved pulley *Z*, loosely mounted on the shaft *B*, while the forward end of said pusher is secured to one end of a spiral spring *U*, the

other end being secured to the frame, as shown. The inner one of the flanges on the shaft is provided with a radial projecting lug *20*, which is engaged by a spring-actuated locking-pawl *21*, which is provided with an extension *22*.

V denotes a releasing-stop, which projects in the path of the movement of the end *22* of the locking-pawl *21* and serves to engage the same when the disk is revolved in the direction of the arrow *40^X*, and *W* denotes a lug secured to the face of the disk, which engages the stop *V* when the said disk turns in its reverse direction after the pawl has been disengaged and limits such movement of said disk.

A⁵ denotes a shaft arranged at right angles to the shaft *B* and in the same horizontal plane, one end of which is provided with a bevel-gear *a⁵*, which meshes with a similar gear *a⁶* on the main shaft *B*, and *B⁵* denotes a cam secured upon said shaft *A⁵*, which engages a projecting arm *c⁵* on a picket-shifting device, such device consisting of a rock-shaft *C⁵*, journaled to the frame to the front of and just below the picket-bed, such shaft having upwardly-projecting arms *c⁶*, pivoted at their upper ends to horizontally-disposed arms *c⁷*, movable transversely across the picket-bed *N*, the rear ends of such arms being turned up, as at *c⁸*.

D⁵ denotes a stout spiral spring connected at one end to the frame, its opposite end being connected to one of the arms *c⁷*, as shown, such spring serving to normally pull the said picket-shifter outward.

E⁵ denotes picket-guides pivoted to the beam *L*, which project over the bed of the machine in the path of the moving picket during its feed forward, the front edges of said guides having downturned flanges *e⁵*, which serve to hold the pickets in proper relation to the twister-disks, springs *e⁶* being provided for holding said guides down in place.

Thus far I have described the construction of the wire-twisting devices and the picket-feed construction. I will now proceed to describe the practical operation of such devices. Assuming the parts to be in the position shown in Figs. 1 and 3, a picket having been pushed in place, its front end engaging a stop-block *30*, the shifter-arms *c⁷* being in their innermost position, their vertical portions *c⁸* engaging the rear edge of the picket, by turning the shaft *B* in the direction of the arrow *x* the radial lug *20* on the flange *C* will engage the locking-pawl and turn the grooved wheel *Z* with it, winding the cord *T* thereon and pulling the pusher backward. It will be observed that when the pusher reaches its outermost limit its finger becomes disengaged from the guide-plates. Now, as the pusher is pulled backward the rear edge of its finger will engage a spring-stop *40* and be forced under the said plates, so as to offer an unobstructed surface on the upper face of the extension and permit a picket to be placed

in position as the pusher travels backward. As the shaft B revolves, the gear D, engaging the gear E' on the shaft E, will cause the crank F to oscillate the segment G, and the 5 teeth thereof, engaging the gear I on the shaft H, cause the rack-bar J to reciprocate in a direction opposite the movement of the said segment, the length of the tooth-section G' being such as to turn the gear I one revolution. 10 The movement of the rack-bar causes the twister-disks to revolve in the same direction as the movement of the segment. It will of course be understood that the toothed portion of the twister-disks may be of such diameter 15 in relation to the rack-bar that one complete movement of such bar in one direction will cause the said twister-disks to revolve one or more times, so as to make one or more twists in the wires. I preferably make such toothed 20 portions one-half the diameter of the gear H', so that the wires are twisted double at each movement of the rack-bar. Following the before-described movement of the segment, it will be observed that at the time the end 50 of the 25 toothed portion passes from under the gear I and the smooth portion thereof passes thereunder a projecting plate 60, fastened to the upper edge of the segment and projected above the smooth portion thereof, engages 30 projections 70 on the face of the gear I and holds same from revolving, it being understood that the construction of the opposite end of the segment is similar, so as to also operate, as described, on its return movement. 35 During the above operation the shaft B causes (through the bevel-gears a^5 a^6) the shaft A⁵ to revolve and bring the cam B⁵ in position about ready to release its pressure against the bar c⁵, the continued or end movement in the direction stated of the segment 40 will cause the cam to release said arm c⁵, which permits the spring D⁵ to quickly draw the bars c⁵ c⁸ outward and with it the picket, the front edge of such picket striking against the inclined portions of the spring-guides E⁵ and lifting them out of the way. At this 45 time the crank F has pushed the segment its full movement in one way and begins to pull it in the opposite direction, the tooth-section 50 now engaging the gear I and causes it, through the gear H', to move the rack J and turn the twisters in the opposite direction and twist the wires at the front edge of the picket last in place. At this time the bolt-reel pulls 55 the said picket forward, in a manner hereinafter described, and allows the spread or parallel portions of the wires to be in position to receive the next picket when it is pushed in place. During this continued 60 movement the cam B⁵ engages the arm c⁵ and pushes it in position, while the large grooved wheel winds up the cord T and pulls the 65 picket-pusher back until it reaches the outer end of the extension, where the top plates Q are stopped short, allowing the spring p to raise the finger to its vertical position, it being understood, however, that before the

pusher reaches the limit of its outer movement another picket has been placed in position upon the extension O. At the time 70 said pusher reaches its outer limit the end 22 of the locking-pawl will strike against the stop V and release the pawl 21 from the lug 20 and permit said wheel and the pusher to be quickly drawn back by means of the spring 75 U, which is secured to the front end of the pusher and frame, as described, the lug W on the face of the wheel engaging the stop V and holds the said wheel from further movement in such direction, thereby getting a continued automatic movement of the twisting, feeding, and shifting devices from a continued movement in one direction of the main shaft. 80

The devices for winding up the complete fence into bolts are most clearly shown in 85 Figs. 1, 2, and 8 of the drawings, such devices consisting, namely, of a swinging frame formed of arms F⁵ F⁶, pivoted at a⁸ to the front beams a⁹ of the frame of the machine. The arm F⁵ is provided at its lower end with 90 a short shaft G⁵, provided with a cog-wheel g⁵, adapted to engage a segmental rack-bar H⁵, fastened to the side of the machine, as shown. On the outer end of the shaft G⁵ is mounted a gear I⁵, which meshes with a bevel-pinion J⁵ on the lower end of a shaft J⁶, journaled in bearings j⁵, projected from the arm 95 F⁵, the upper end thereof being also provided with a bevel-gear K⁵, of a much larger diameter than the gear J⁵, such gear K⁵ engaging a bevel-pinion L⁵ on the end of the disk L⁶, journaled in the outer end of the arm 100 F⁶, such disk being provided with a non-circular socket l⁵, in which is fitted the squared end of the bolt-shaft L⁷, its opposite end being detachably supported in the arm F⁶, as 105 shown.

M⁵ denotes a lever-arm loosely pivoted on the disk L⁶, provided with gravity-pawls l⁵ l⁵, which engage a toothed section N⁵, formed 110 upon the disk L⁶, said arm adapted when moved outward to turn the said disk L⁶ and with it the shaft L⁷ in the direction indicated by the arrow in Fig. 2, spring-actuated pawls O⁵ O⁵, pivoted upon the end of the arm 115 F⁵, being provided to hold said toothed section N⁵ from reverse movement.

P⁵ indicates a sliding collar secured upon the lever M⁵, which may be adjusted on said lever, as desired, and held in such adjustment 120 by means of a rod Q⁵, pivoted at its upper end to the collar P⁵ and at its lower end to the frame, as shown. By adjusting the collar-bar from the disk L⁶ the bolt-reel may be revolved a greater or less distance, so as to 125 pull the last picket woven away from the picket-bed to a greater or less degree, whereby the fence-pickets may be woven close together or apart, as may be desired.

R⁵ indicates a pitman connected at one end 130 to the collar P⁵ and at its opposite end to a crank-arm S⁵ on the outer end of a short shaft T⁵, journaled in the frame at right angles to the shaft B, which is provided with a bevel-

gear t^5 , which meshes with a bevel-gear a^{10} on the shaft B, as shown.

In operation when the machine is first started the bolt-shaft L^7 is adjusted so as to be nearly flush with the upper edge of the frame of the machine. The end of the wires are then secured thereto and the machine set in motion and operated in the manner before described. It will be seen that as the shaft B revolves its gear a^{10} will revolve the shaft T^6 and cause the pitman to oscillate the lever-arm M^5 and rotate the shaft L^7 and wind the fence material thereon, it being understood that the relation of the crank S^5 , the shaft T^6 , and their connection with shaft B is such that it will operate to wind up the fence material just after the picket-shifter pulls the pickets away from the twister-disks, as before described. It will also be seen that as the bolt-shaft L^7 is revolved the pinion L^5 will slightly turn the large pinion K^5 on the shaft J^6 , which in turn will impart motion to the gear I^5 on the outer end of the shaft G^5 , and the cog-wheel g^5 on said shaft, engaging the segmental rack H^5 , will cause the lower end of the swinging arms F^5 F^6 and the mechanism supported thereon to be elevated, the outer end of such arms at the same time gradually lowering. By this construction I am enabled to wind up a fence-bolt of a very large diameter and at the same time maintaining the same tension on the fence material as it is in course of being wound. After a bolt of fence material of sufficient size has been wound up the wires are cut and the shaft pulled out from the end X, thereby permitting said bolt to be quickly removed, and by reinserting the shaft and securing the wires thereto the machine is again ready for operation. After the arms have been automatically lowered to the farthest extent they may be quickly brought to their upper position by releasing a stop-pawl 51, which holds the lower end of the shaft J^6 and its gear J^5 in engagement with the gear I^5 , said shaft being journaled in an elongated opening in the bearing j^5 . (See Fig. 1 at 1^a.)

Having thus described my invention, what I claim, and desire to secure by Letters Patent, is—

1. In a fence-making machine, the combination, with the main frame having a picket support or bed, a series of twister-disks disposed adjacent to and above said bed, and a main drive-shaft mounted in said frame, of an oscillating toothed segment, intermediate connections between said segment and the main shaft whereby said segment is reciprocated by the continued revolution of said main shaft, and intermediate cog-wheel and rack-bar devices between said segment and the twister-disks, whereby said disks are revolved in opposite directions by the oscillating movement of the segment, substantially as and for the purpose described.

2. In a fence-making machine, the combination, with the main frame having a picket

support or bed and a series of twister-disks having gear-wheel portions disposed adjacent to and above said bed, and a main driving-shaft journaled in said frame provided with a gear-wheel D, of the shaft E, provided with a gear E', engaging the gear D, said shaft E provided with a crank-arm F, an oscillating segment G, having an upper cog-surface, the pitman f, connecting said segment and the crank-arm, the shaft H, provided with a gear I, adapted to engage the toothed portion of the segment and a cog-gear H', a reciprocating bar J, provided with an upper rack-surface engaging said toothed twister-disks, and a lower rack-surface engaging the gear H', all arranged substantially as and for the purpose described.

3. In a fence-making machine, the combination, with the main frame having a picket-supporting bed, a main drive-shaft journaled in said frame provided with a gear a^6 , a shaft A^5 , journaled at right angles to the main shaft and geared therewith, and a cam secured upon said shaft A^5 , a rock-shaft C^5 , journaled to the frame in front of the picket-bed provided with a depending arm c^5 , adapted to engage the cam, and upwardly-projecting arms c^6 c^6 and horizontal arms c^7 , hinged at the upper ends of the arms c^6 , said arms c^7 operating transversely over the picket-bed and adapted to engage said pickets and pull them away from said bed by the movement of the shaft A^5 and its cam, and means for normally pulling said arms to their outward position, substantially as and for the purpose described.

4. In a fence-making machine, the combination, with the main frame having a picket-supporting bed, the main drive-shaft B, provided with fixed flanges, one of said flanges having a radial lug, a disk X, loosely mounted on said shaft between said flanges provided with a spring-actuated pawl adapted to be engaged by said radial lug to turn said disk with the shaft, and a stop secured to the frame for disengaging the pawl and lug, of the picket-bed extension O, the reciprocating picket-pusher operating thereon, a pulley mounted on the outer end of said extension, a cord S passed thereover and connected to the pusher and the disk Z, and the spring U for drawing the pusher forward as the pull on the cord S is released, substantially as and for the purpose described.

5. The combination, with the main frame provided with a picket-supporting bed formed with a lateral extension O, said extension provided with a longitudinal slot, and guide-plates projecting over the upper edge of said slot, of a picket-pusher reciprocating in said slot, said pusher consisting of a body portion operating in the slot and a pushing-finger projected above said slot, and means for reciprocating said pusher, substantially as and for the purpose described.

6. The combination, with the main frame provided with a picket-bed having an exten-

5 sion O, provided with a longitudinal slot, the
guide-plates Q Q and n n, fitted, respectively,
on the upper and lower faces of the said ex-
tension and projected over said slot, the plates
5 Q Q, stopped short at each end of the exten-
sion, and the spring-catch 40 at the front end
10 of the upper plates, of the picket-pushers P,
consisting of a body portion P', having side
grooves p, adapted to engage the plates n n,
15 an upwardly-projecting finger P², pivoted at
its lower end to the body, the spring P³, said
finger provided with grooves p⁴ p⁴, adapted to
engage the plates Q Q, said finger adapted to
20 engage the spring 40 on its return movement
and be thereby forced under the plates Q Q,
25 and means for reciprocating the pusher, sub-
stantially as shown and described.

7. In a fence-making machine, the combi-
nation, with the main frame provided with a
20 picket support or bed, of the spring-actuated
picket-guides E⁵, pivoted to the frame to
swing in the path of the longitudinal move-
ment of the picket, said guides provided with
25 inclined outer edges e⁵ for holding the pickets
in position, substantially as and for the pur-
pose described.

8. The combination, with the main frame
having a picket support or bed, the main
drive-shaft journaled therein, picket-twisting
30 devices mounted in said frame, and means
for operating the twisting devices, of a bolt-
shaft L⁷, journaled on the frame parallel to
the picket-bed, a counter-shaft T⁵, geared with
35 the main shaft B, and intermediate connec-
tions between said shaft B and the bolt-shaft
L⁷, whereby the continued revolution of the
main drive-shaft will impart a vertically-re-
ciprocating and rotary motion to the bolt-
40 shaft, substantially as and for the purpose
described.

9. The combination, with the main frame
provided with a picket-supporting bed, the
wire-twisting devices, and the main drive-
45 shaft journaled in the frame, of the bolt-shaft
L⁷, journaled on the frame, provided with a
disk having a toothed section at one end fixed
to turn therewith, an oscillating lever loosely
mounted on said disk provided with gravity-
50 pawls engaging said toothed section, a coun-
ter-shaft T⁵, geared with the main shaft, a

crank secured upon the end of said counter-
shaft, and a pitman, one end thereof connected
to said crank, its opposite end connected to a
sliding collar adjustably held on the arm of
55 the lever, substantially as and for the pur-
pose described.

10. In a fence-making machine, the combi-
nation, with the drive-shaft B, the counter-
shaft T⁵ geared therewith provided with a
crank-arm, and the segmental rack H, of the
60 centrally-pivoted bars F⁵ F⁶, a disk L⁶, loosely
journaled in the arm F⁵, having a non-circu-
lar socket and a bevel-gear portion L⁵, the
bolt-shaft L⁷, having a non-circular end fit-
ting said socket, supported at its opposite
65 end in the arm F⁶, a toothed section N⁵ on
said disk L⁶, the lever M⁵, having a pivotal
pawl engaging said toothed disk, the shaft J⁶,
provided with a gear K⁵, meshing with the
bevel-gear L⁵, the gear J⁵ on the lower end of
70 the shaft J⁶, the counter-shaft G⁵, provided
with a gear I⁵, meshing with gear J⁵ and with
a cog-wheel g⁵, adapted to engage the rack
H, and a pitman-connection between the
crank-arm S⁵ and the lever M⁵, all arranged
75 substantially as and for the purpose de-
scribed.

11. In a fence-making machine, the combi-
nation, with the main frame and a main
drive-shaft journaled thereon, of the wire-
twisting devices, a reciprocating picket-
pusher adapted to automatically insert the
80 pickets between the wires, a picket-shifter
for pulling the pickets from the picket-bed, a
bolt-shaft journaled to the frame adapted to
85 wind up the woven fence material, and in-
termediate connections between said wire-
twisters, picket-shifter, picket-shifter, the
bolt-shaft, and the main drive-shaft, whereby
said devices are automatically operated at
90 predetermined intervals by a continuous revo-
lution of the said drive-shaft, all arranged
substantially as and for the purpose set forth.

In testimony whereof I affix my signature in
presence of two witnesses.

JAMES KELLEY.
